UNITED STATES PATENT OFFICE

2,516,581

WELL TOOL

John Lynes and James A. Armitage, Houston,
Tex., assignors to Lynes, Incorporated, Houston,
Tex., a corporation of Texas

Application November 24, 1944, Serial No. 564,919

6 Claims. (Cl. 166—11)

1

The invention relates to a well tool which is particularly adapted for positioning in the well with a view of sealing off an area, a formation, portion of a pipe or screen, or for any particular purpose such as for treating, testing, or cementing.

In providing a tool which must be lowered into a well bore for great distances and then manipulated for opening and closing the tool or to effect circulation above the tool or to discharge or intake fluids relative to the well bore below the tool, it is desirable to have a tool with as few moving or operating parts as possible because all of the parts of the tool are immersed in the drilling fluid or well liquid and are subjected to tremendous pressures and often high temperatures, so that the possibility of the parts sticking or leaking is minimized with the reduction in the number of movable parts.

It is one of the objects of the invention to provide a well tool which is made up of a pipe and one or more packers suspended thereon which are adapted to be inflated to form a seal in the well.

Another object of the invention is to provide a well tool, including a hydraulically inflatable packer whereby a single pipe is utilized to both carry and inflate the packer and to serve as a conduit for the discharge or inlet of fluids relative to the well.

Still another object of the invention is to provide a well pipe having one or more packers suspended thereon in a slideable position in such a manner that liquid forced from the pipe will inflate the packers so as to cause longitudinal contraction of the packers so that slight movement of the pipe will then open the tool to the formation.

Still another object of the invention is to provide a hydraulic packer for a well bore which is supported on an operating pipe in such a manner that the inflation of the packer will on slight movement of the pipe open the pipe for discharge or inlet of liquid or fluid.

Still another object of the invention is to provide an operating pipe and a well packer therefor, which is movably suspended upon the pipe so that after the packer has been set the pipe may be moved relative to the packer so as to either circulate above the packer or effect a discharge or inlet of fluid to or from the well below the packer.

Still another object of the invention is to provide a treating or testing tool having a single operating pipe which may be used to lower the tool into the well, wash the well, inflate the

2

packer, and discharge or intake fluid relative to the tool.

Still another object of the invention is to provide a hydraulically inflatable tool where an opening from the operating pipe is normally disposed within the confines of the deflated packer, and which may be uncovered to open the tool to an area outside of the packer after inflation of the packer.

10 Still another object of the invention is to provide a simple and economical treating, testing, cleaning, and cementing tool for wells wherein a packer may be inflated solely by the application of hydraulic pressure through the pipe and the pipe opened by sliding the inflating opening out of the packer.

Another object of the invention is to provide a well tool having an inflatable packer wherein the same opening in the operating pipe is utilized 20 to inflate and deflate the packer and for inlet and outlet for the tool.

Still another object of the invention is to provide a well tool which may be lowered into a well bore in a normally closed position, the packer inflated, the well washed above the packer, and the tool then opened to the formation.

A still further object of the invention is to provide a well tool wherein a hydraulic packer may be inflated or deflated and access had to a sealed off formation solely by the use of an operating pipe.

Other and further objects of the invention will be readily apparent when the following description is considered in connection with the accompanying drawings, wherein—

Fig. 1 is a diagrammatic illustration of the tool in normally assembled position ready to be lowered into the well bore.

Fig. 2 is a vertical sectional view of the upper end of the upper packer of the tool of Fig. 1.

Fig. 3 is a vertical sectional view of the lower end of the lower packer of the tool of Fig. 1.

Fig. 4 is a side elevation of the tool with the packers inflated in position in the well bore.

Fig. 5 is a vertical sectional view of the upper packer of the tool of Fig. 4.

Fig. 6 is a vertical sectional view of the lower packer of the tool of Fig. 4.

Figs. 7, 8, and 9 show three different positions of a slightly modified form of the tool, wherein provision has been made for washing or circulating in the well above the packer.

As best seen in Figs. 1 to 3 inclusive, the tool is made up of the pipe 2 having a swivel collar 3 therein so that the pipe 2 may be rotated rela-

tive to the tool 4. This swivel may be of any desired form, usually embodying anti-friction bearings which serve to transmit any load through the swivel while permitting rotation of the pipe which extends in opposite directions therefrom.

The pipe 2 extends on through the swivel as best seen in Fig. 2 and has a coil spring 6 there-around whose upper end 7 abuts the swivel 3 while the lower end 8 thereof rests upon the annular ring 10 which is slidably arranged about the pipe 2.

An outstanding flange 11 is fixed to the pipe 2 and has a plurality of openings therein to receive the suspension bolts 12 which are threaded at 13 into the upper fitting 14 of the upper packer 15. In this manner as seen in Fig. 2, this upper packer is suspended from the flange 11 in normal position when the packer is not inflated and normally retained from sliding on the pipe because the ring 10 is pressed against the bolt heads by the spring 6.

The packer 15 is made up of the upper fitting 14 and the lower fitting 16 which are spaced apart by the resilient packing 17, which is suitably affixed to the bushings as at 18 at each end in accordance with the detail construction disclosed and claimed in the copending applications of Lynes, Serial No. 65,843, filed December 17, 1948, which is a continuation of Serial No. 473,928, filed January 29, 1943, for High Pressure Inflatable Packer and Assembly for Testing and Treating Well Formations, now abandoned, and Serial No. 559,338 filed October 19, 1944 for Well Formation Tool and Packer Therefor.

For purposes of description here, it may be said that this packing is made up of a packing sleeve 20 having the reinforcing wires or strands 21 embedded therein in combination with the internal liner 22 which tends to seal the connection for the other portions of the packer.

In order to provide a seal with the periphery 23 of the pipe 2, the inside of the packing has the seal rings 24 in position and the fitting 14 may have a plurality of packing rings 25 to assist in maintaining the seal about the pipe.

The lower fitting 16 is arranged in a manner similar to the upper fitting 14 in that such fitting is slidable on the pipe.

The lower packer 25, illustrated generally in Fig. 3, is identically constructed and is suspended from the intermediate or middle flange 26 by the bolts 12 while the lower fitting 28 is somewhat longer than the fitting 16 of the upper packer.

One or more openings 30 in the pipe 2 are arranged so that they are disposed within the confines of the packer 15 when the packer is deflated. When liquid is forced down through the pipe 2, it will discharge through these openings 30 to the interior 30' of the packer 15 and cause inflation of the packer.

It seems obvious that as this packer is enlarged radially and circumferentially due to inflation, that of necessity it will contract longitudinally. The present tool is of such a simple and economical construction and arrangement that the positioning of this opening 30 is such that the first application of pressure will cause inflation and the longitudinal contraction of the packer to such an extent that the lower fitting 16 will move up to a position such that the ring 24 will almost cover the opening at about the time the inflation is completed. The packer is now firmly engaged against the wall of the well or the pipe in the well in which it is positioned

so that the pipe 2 may be lowered slightly to move the opening 30 into the fitting 16. This traps the liquid in the packer to lock the packer in an inflated position. Any additional movement of the pipe will uncover the opening as seen in Fig. 5.

In other words, when the packer is deflated, the opening 30 will be inside of the packer but when the packer is inflated and the pipe lowered slightly relative to the packer, the opening will first move into the fitting 16 to lock the liquid that is in the packer in such confined position so the packer will remain inflated, and continued movement will then move the opening 30 on through the fitting 16 into the opening 31 in the well bore 32 as best seen in the bottom of Fig. 5. In this manner the tool is opened with a view of performing any desired operation. As seen in Fig. 5, it will be noted that the lowering of the pipe 2 relative to the packer has caused the flange 11 to slide downwardly along the bolts 12 while the ring 10 has been held stationary by the upper ends of the bolts. The swivel 3 has moved down with the pipe and this has caused some compression of the spring 6.

The packer is thus inflated with a known pressure which is preferably sufficient to hold the packer in sealing position with the wall of the well or the pipe in which it has been set so as to support the load of any liquid which may be in space 33 in the well above the packer.

The amount of lowering of the pipe may be gauged or measured if desired, and the pipe may have all or part of the liquid removed after the packer is inflated and while the opening 30 is in the lower fitting 16 if an operation is to be performed where it is desired that there be a lesser static pressure in the pipe than at the formation or location where the tool is to be opened. Of course if any particular liquid is to be discharged from the tool, such liquid may be used as the inflating liquid if desired, but if it is a liquid unsuitable for inflating the packer or packers, then a desired quantity of suitable liquid may be first inserted in the pipe so that the first applied pressure will cause the suitable liquid to move into the packers and after the packers are closed by movement of the pipe the tool is then opened.

In releasing the tool it is only necessary to lift or raise the pipe slightly to return the ports 30 to the interior of the packers and if there is an excess of pressure in the well bore over that in the pipe, the packers will deflate. The inherent resiliency of the packers assists in the deflation but if the packers should become stuck, an upward pull on the pipe raises the flange 11 and a consequent upward pull is exerted on the upper end of the packer to pull it loose.

The foregoing description has been given in connection with a single packer and where such a single packer is used, a suitable bull plug, float shoe, or other member 34 will be threaded onto the lower end of the pipe 2. This may be directly below the openings 30 if a single packer is used or it may be attached to the lower end 35 of the pipe 2 as seen in Fig. 6.

The lower packer 25 is seen generally in Fig. 6 and its construction and operation will be the same as that of the upper packer 15. There may be a slight difference in that the lower fitting 23 is somewhat longer than the fitting 16 on the lower end of the upper packer 15 because it may not be desirable to open the tool into the space 38 below the lower packer 25. In this manner the opening 30 will not be uncovered as the pipe

is moved down but will lock the liquid in the packer 25 and then remain covered or closed while the openings 30 between the packers will tend to open the tool.

Very often in operating a tool of this sort it is desirable to lower the tool into position in the well and before the packers are inflated, it may be desirable to wash the well or to circulate liquid for some reason or other. To accomplish this, the lower end 35 of the pipe 2 has been provided with openings 40 so that circulation may be had. When it is desired to set the packers, a go-devil 41 can be dropped through the operating pipe 2 so as to land in position as seen in Fig. 6. Suitable packings 42 are arranged inside of the pipe 2 so as to form a seal with the go-devil and close the openings 40. A spear-head 43 on the go-devil permits its recovery after the operations have been performed and it is desirable to again circulate in the well if the tool is to be moved to another location or removed from the well. As seen in Fig. 3 these openings 40 will be normally open when the packers are deflated and the tool is being lowered into the well bore.

It seems obvious that the tool may be arranged to operate with either one or two packers, depending upon the operation to be performed, the location of the area to be operated on, treated, tested, cemented, or cleaned.

Figs. 7, 8, and 9 show a slightly modified form of the mechanism wherein an arrangement has been provided to determine the position of the pipe relative to the packers and which will permit circulation through the well above the packers after the tool has been lowered into the well. This arrangement as seen in Fig. 7 includes a coupling 45 which is threaded at 46 into the upper fitting 14 of the packer on the tool or the upper packer if two packers are used. This coupling is provided with an internal chamber 47 which is arranged to receive a flange 48 which is quite similar to the flange 11 and bolt arrangement 12 in that the flange abuts against a shoulder 49 in a circulation head 50 so that the spring 6 pressed against the upper end 51 of this head normally holds the packer against sliding movement. This arrangement is desired in order to hold the opening 52 in position in the flow-head 50 so that it will be closed going into the well bore by being positioned between the two spaced packings 53.

When, however, the tool is to be operated, pressure can be applied through the operating pipe which will pass outwardly through the openings 30 to cause inflation of the packer so that it will form a seal at 55 with the well bore or pipe in which the tool is being set. When such a seal is made, then the pipe 2 will be lowered slightly so as to move the opening 52 downwardly into alignment with the circulating ports 56 arranged in the circulating head 50. In this manner circulation can be had in the well bore so as to wash the space 33 above the upper packer as seen in Fig. 5. This downward sliding movement of the pipe 2 to align the ports 52 and 56 will also lock the liquid in the packers by moving the port 30 into the lower fitting 16 of the packer. In this manner the well can be sealed and washed prior to the opening of the tool.

The next step as seen in Fig. 9 will be an additional lowering of the pipe 2 so as to cause the port 52 to move out of alignment with the discharge port 56 so that it will in turn be sealed in the flow-head 50 between the two spaced packings 57. This lower position is insured due to the fact that the shoulder 58 of the upper fit-

ting 14 now receives the flange 48 so that the operator knows that by lowering his pipe until it will not move downwardly any more due to the fact that the load of the pipe or a portion thereof at least is supported by the packer. The driller will receive this indication by looking at his weight indicator.

This downward movement closes the tool above the packer. It opens the tool below the packer due to the fact that the opening 30 moves out of the fitting 16 at the lower end of the packer due to the last lowering operation.

When the desired operation has been performed, it is only necessary to lift slightly the pipe 2 in order to close the tool and if desired the reverse steps may be performed so as to again open the ports 56 and permit circulation either to replace heavy liquid in the well so as to avoid a blow-out when the packer is released or for the purpose of washing material away above the packer. The opening of the ports 56 may also serve to wash out the operating pipe 2 above the tool.

If a pressure is to be retained on the formation, the pipe 2 will be raised so as to move the ports 30 back into the fitting 16, locking any pressure in the area 31 in the well bore below the tool or of course the pressure may be held in the operating pipe 2 on the area below the packer as long as desired, but in such instance, the pipe would not be raised from the position of Fig. 9, whereas, if the pressure were to be locked and circulation had in the well above the packer, the pipe would be raised to the position of Fig. 8.

When the operation has been completed and it is desired to remove the tool, the pipe will be raised an additional amount to the position of Fig. 7 so that the opening 13 moves back into the interior of the packer so as to allow the packer to deflate. This deflating operation is normally insured due to the fact that the packing is resilient and will tend to return to a deflated position. If, however, the packer should not deflate, the pipe 2 may be raised so that the flange 48 abuts the shoulder 49 and a pull can thus be exercised on the upper end of the packer, tending to draw it out of sealing position.

Broadly, the invention contemplates a tool which can be used for a great number of different operations in the well bore such as the treating of the formation by discharging liquid there-into, the testing of a formation by drawing liquid from the formation into the tool, the cementing or squeezing of a formation with liquids applied under pressure through the tool or the cleaning of the screen or strainer in the well.

The simple operation of having only one moving part which is the pipe movable relative to the packer provides a tool which is fool-proof and which insures successful manipulation in the well bore.

What is claimed is:

1. A well tool comprising an operating pipe extending to the top of the well, upper and lower spaced hydraulically inflatable packers thereon, means slidably supporting said packers on said pipe, an opening through said pipe disposed within each packer when deflated to direct liquid under pressure into the packers to inflate the packers, said packers being contractible longitudinally upon inflation, the upper of said packers having a lower fitting slidable on said pipe and disposed below the opening in the pipe for the

7
upper packer when the packer is deflated, a fluid excluding seal in said fitting about said operating pipe, said pipe being slidable to a position to move such opening as the packer is inflated to a position below said lower fitting so that the pipe is thus opened to the area between the packers.

2. A well tool comprising an operating pipe extending to the top of the well, upper and lower spaced hydraulically inflatable packers thereon, means slidably supporting said packers on said pipe for limited longitudinal movement thereon, an opening through said pipe disposed within each packer to direct liquid under pressure into the packers to inflate the packers, said packers being contractible longitudinally upon inflation, the upper of said packers having a lower fitting slidable on said pipe and disposed below the opening in the pipe for the upper packer when the packer is deflated, a fluid excluding seal in said fitting about said operating pipe, said pipe being slidable to a position to uncover such opening as the packer is inflated to a position below said lower fitting so that the pipe is thus opened to the area between the packers, said pipe within the packer being a blank pipe when the packer is inflated after the movement of said opening out of the packer due to the fitting moving above said opening and serving to lock the packer in inflated condition, said pipe having limited movement relative to the set and locked packer so as to return the opening back into the packer to release and deflate the packer.

3. A well tool comprising an operating pipe extending to the top of the well, upper and lower spaced hydraulically inflatable packers thereon, means slidably supporting said packers on said pipe, an opening through said pipe disposed within each packer when deflated to direct liquid under pressure into the packers to inflate the packers, said packers being contractible longitudinally upon inflation, each of said packers having a lower fitting slidable on said pipe and normally disposed below the said opening in the pipe within the packer when the packers are deflated, a seal in each fitting about said pipe, said fitting of the upper packer being slidable to a position to cover such opening when the packer is inflated, said pipe being slidable relative to the upper packer so that the opening for the upper packer may be moved below the fitting thereof so that the pipe is thus opened to the area between the packers.

4. A well tool comprising a pipe extending to the surface, an inflatable packer sealed thereon, means slidably supporting said packer on said pipe, and an opening in said pipe which is normally disposed within the deflated packer and opening into said packer to effect inflation by

8
the application of liquid pressure in the pipe, said packer being contractible longitudinally along said pipe as it inflates, said packer supporting means permitting slidable movement of the pipe relative to the inflated packer so as to uncover said opening for the discharge or intake of fluid.

5. A well tool comprising a pipe extending to the top of the well, a pair of hydraulically inflatable packers, means slidably mounting said packers on said pipe whereby said pipe is slidably in said packers, each packer comprising end fittings and an inflatable sleeve therebetween, means to slidably seal said fittings upon said pipe, openings in the pipe to direct liquid into said packers to inflate the packers, the ends of said packers being movable on the pipe for contraction of the length of the packer on the pipe to facilitate radial expansion of said sleeve.

10 6. A well tool comprising an operating pipe extending to the top of the well, upper and lower spaced hydraulically inflatable packers thereon, means slidably mounting said packers on said pipe, an opening through said pipe disposed

15 within each packer when deflated to direct liquid under pressure into the packers to inflate the packers, said packers being contractible longitudinally upon inflation, each of said packers having a lower fitting slidable on said pipe and

20 normally disposed below the said opening in the pipe within the packer when the packers are deflated, a seal in each fitting about said pipe, said lower fitting of the upper packer being slid-
able to a position to cover such opening when

25 the upper packer is inflated, said pipe being slid-
able relative to the inflated upper packer so that the opening for the upper packer may be moved below the fitting thereof so that the pipe is thus opened to the area between the packers, the

30 spacing of said lower fitting on the lower packer with respect to such lower packer opening in the pipe being such that such lower fitting covers the opening for the lower packer when the tool is opened between the packers.
